J. T. DOYLE

TRACK GAUGE

Filed May 21, 1921

UNITED STATES PATENT OFFICE.

JOHN T. DOYLE, OF SAN FRANCISCO, CALIFORNIA.

TRACK GAUGE.

Application filed May 21, 1921. Serial No. 471,423.

To all whom it may concern:

Be it known that I, JOHN T. DOYLE, a citizen of the United States, residing in the city and county of San Francisco and State of California, have invented a new and useful Improvement in a Track Gauge, of which the following is a specification.

My invention relates to improvements in track gauges wherein hooks slidably mounted within the bar of the gauge operate in conjunction with wedges to move an adjacent rail into contact with the gauge lugs.

The primary object of the present invention is to provide a new and improved track gauge having means for moving the rails to the correct gauge.

Another object of the invention is to provide a new and improved device of the character described having few parts of simple and cheap construction and which may be easily and quickly operated, thereby effecting a saving of time and labor in moving rails to the proper distance apart.

I accomplish these and other objects by means of the improved device disclosed in the drawings forming a part of the present specification wherein like characters of reference are used to designate similar parts throughout the said specification and drawings, and in which:

Fig. 1 is a broken plan view of my improved track gauge applied to a pair of rails; and

Fig. 2 is a broken side elevation of Fig. 1.

Referring to the drawings the numeral 1 is used to designate a channel bar having the usual gauge lugs 2 mounted upon each end thereof. The gauge lugs 2 are arranged at right angles to the bar 1 so that a line drawn across the faces of said lugs 2 will be at right angles to the center of said bar 1 and consequently a pair of rails 3, the inner side of the heads of which are in contact with the said lugs 2, will be parallel to each other.

The ends 4 of the channel bar 1 rest upon the heads of the rails 3 in order to facilitate proper alignment of the lugs 2 with the inner sides of the heads of the rails 3.

The channel bar 1 is provided with horizontally disposed slots 6 adjacent each end thereof and arranged slightly above the lugs 2.

Slidably mounted within each end of the channel bar 1 is a hook 7 arranged to engage the outer sides or surfaces of the webs

9 of the rails 3, said hooks 7 having slots 8 therein arranged to substantially register with the slots 6 of the channel bar 1 when the rails 3 are engaged by said hooks as above described and the inner sides of the heads thereof are in contact with the gauge lugs 2.

Wedges 11 are slidably mounted within the registering slots 6 and 8 and are provided with suitable stops 10 to normally prevent inadvertent removal of said wedges from said slots.

The hooks 7 are also provided with lugs or projections 12 on the inner ends thereof, which lugs or projections 12 extend or project above the upper surface of the channel bar 1 so that said wedges 11 may be easily projected to their outermost positions by a blow struck with a sledge or other suitable tool upon said lugs 12.

In operation the hooks 7 are moved to their outermost positions so that the curved portions of said hooks may freely pass over the heads of the rails 3 and engage the outer sides of the webs 9 of the rails 3. The wedges 11 are now moved inwardly to engage the ends of the slots 6 and 8 and by striking repeated blows upon the larger ends of the wedges the hooks 7 engage the outer sides or side 85 of the web 9 of the adjacent rail 3 and thereby move the inner side of the head of said rail 3 into contact with the adjacent gauge lugs 2, thereby producing the correct gauge for the said parallel rails.

After the rails are spiked in this correct position a blow struck upon the smaller ends of the wedges 11 will cause said wedges to disengage the ends of the slots 6 and 8 and a second blow or blows upon the projections 12 of the hooks 7 will move said hooks to disengage the webs 9 of the rails 3 when the entire gauge or channel bar 1 may be moved along the rails to the next position.

Having thus described my invention what I claim as new and desire to secure by Letters Patent is:

1. A track gauge comprising a channel bar having gauge lugs and horizontally disposed slots adjacent each end thereof; a hook slidably mounted within each end of said channel bar and having a slot therein arranged to register with the slot in the bar, said hook being arranged to engage the outer side of the web of an adjacent rail; and a wedge slidably mounted within the regis-

tering slots in the bar and hook and arranged, when moved in one direction to actuate the hook to move the inner side of the head of said rail into contact with the 5 adjacent gauge lugs.

2. A track gauge comprising a channel bar having gauge lugs and horizontally disposed slots adjacent each end thereof; a hook slidably mounted within each end of said 10 channel bar and having a slot therein arranged to register with the slot in the bar, said hook being arranged to engage the outer side of the web of an adjacent rail; and a wedge slidably mounted within the registering slots in the bar and hook and arranged, when moved in one direction to actuate the hook to move the inner side of the head of said rail into contact with the 15 adjacent gauge lugs; and means for moving 20 the hooks to disengage said webs.

3. A track gauge comprising a channel bar having gauge lugs and horizontally disposed slots adjacent each end thereof; a hook slidably mounted within each end of the channel bar and having a slot therein 25 arranged to register with the adjacent slot in the bar and likewise provided with upwardly projecting lugs projecting above said channel bar, said hook being arranged to engage the outer side of the web of an adjacent rail; and a wedge slidably mounted within each set of registering slots in the bar and hooks and arranged, when moved in one direction, to actuate the hook to move the inner side of the head of an adjacent 30 rail into contact with the adjacent gauge lugs. 35

In witness whereof I hereunto set my signature.

JOHN T. DOYLE.
